UNITED STATES PATENT OFFICE.

THOMAS SHIPLEY, OF YORK, PENNSYLVANIA.

REFRIGERATING OR ICE-MAKING APPARATUS.

1,226,391.

Specification of Letters Patent. Patented May 15, 1917.

Application filed September 28, 1916. Serial No. 123,655.

To all whom it may concern:

Be it known that I, THOMAS SHIPLEY, of York, in the county of York and State of Pennsylvania, have invented a certain new and useful Improvement in Refrigerating or Ice-Making Apparatus, of which the following is a specification.

My invention relates to refrigerating or ice-making apparatus of the kind in which a compressor pump is used to keep the ammonia or other refrigerating agent in circulation. In such an apparatus or system, the circulation, as is well known, is from the discharge side of the compressor, to and through the condenser, thence to and through the refrigerating or expansion coil, and thence back to the suction side of the compressor—the flow of the ammonia, in normal operation, being away from the compressor on the discharge side, and toward the compressor on the suction side, as diagrammatically illustrated, for example, in Figure 1 of the drawings of my Patent No. 1,079,610 of November 25, 1913.

In the operation of a gas compressor, there is always danger of breaking its head, or some other part of it or its immediate connections, with consequent peril to life and property, due to the escape of ammonia attendant upon said breakage.

To guard against the escape of the ammonia from the discharge side of the system in case of such breakage, is a comparatively simple matter, all that is required being the installation in the discharge line of a check valve opening in the direction of the normal flow of the ammonia therein, but adapted to be seated or closed by superior back pressure from the condenser side of the valve. But to prevent the escape of the ammonia from the suction side of the system (which, it may be remarked, contains the major portion of the ammonia charge), a thus-arranged check valve would not serve the purpose, because the flow of ammonia on the suction side of the system is toward the compressor, and consequently a check valve normally opening in the direction of this flow would *a fortiori* remain open in event of any breakage on the suction side between it and the compressor, thus permitting, in these circumstances, the escape of the gas from the suction side of the system without hindrance.

It is the object of my invention to remedy this difficulty; and this object I attain by

installing at a suitable point in the suction line of the system, between the refrigerating coil and the compressor, a check valve whose closing movement is in the direction of the flow of the ammonia in the suction line, in combination with means extraneous to, and independent of, the ammonia circulating system for exerting upon the check valve a superior pressure in a direction to open it and hold it open, during the normal operation of the apparatus, against the pressure in the suction line, said check valve being closed by the pressure in the suction line whenever the superior pressure exerted by said extraneous means is removed. The means which I prefer for this purpose comprise a fluid agent, such as oil; a pipe line through which said agent is conveyed to the point where it is to act upon the check valve; and a force pump connected to, and driven from, the same engine which drives the compressor, and operating to force the fluid agent through the pipe line to the point where it is to exert its pressure upon the check valve. Suitable means are provided for relieving pressure in the oil pipe line, or pump line as it may be termed, in excess of a predetermined limit; a "bleeder" is provided at a suitable point in the pump line between the pump and the check valve for certain purposes hereinafter mentioned; and means are provided for returning the liquid escaping through the relief appliance, as well as through the "bleeder", back into the pump reservoir.

These, however, as well as other features of my invention, can best be explained and understood by reference to the accompanying drawings in which I have represented the embodiment of the same which, on the whole, I at present prefer.

In said drawings—

Fig. 1 is a perspective view, largely diagrammatic and divested of constructional details, of an apparatus embodying my improvements.

The remaining figures are on a much enlarged scale.

Fig. 2 is an axial vertical section of the suction check valve case, with its contained parts—mostly in elevation.

Fig. 3 is a vertical section of the oil pump on line 3—3 Fig. 5.

Fig. 4 is a like section of the same on line 4—4 Fig. 5.

Fig. 5 is a plan of the same.

Fig. 3 is a side elevation of the same showing the mechanism for driving the shaft which carries the eccentric for operating the pump plunger.

5 Fig. 7 is a sectional elevation, in a measure diagrammatic and divested of detail, of a "remote control" device for relieving pressure in the pump line.

In Figs. 4 and 6 the counter-weighted 10 control valve and its housing and fittings are omitted.

Fig. 1 represents in perspective a twin cylinder, single-acting, vertical, ammonia compressor, of well known type, with so 15 much of its connections to the discharge side and the suction side respectively of the apparatus as needed for the purposes of explanation.

A are the compressor cylinders. 20 B is the header leading from the suction side of the system to the suction ends of the cylinders A through branch pipes B'.

Pipes Z, similarly arranged, lead from the discharge ends of the compressor cylinders, as will be understood without further explanation. The circulating system, as shown by dotted lines, is from the discharge side of the compressor, through the branch pipes Z and main discharge line to which 30 they are connected, to "condenser," thence to "refrigerating coil," and thence through the suction line B, B', back to the suction side of the compressor.

X is the main crank shaft of the engine, 35 from which the pistons of the compressor cylinders are driven through the usual connections. All these parts may be of any ordinary or usual construction.

At the junction of the suction line B with 40 the branches B' B' is located the suction check-valve, whose case or shell is shown at C.

D is the casing of the pump whose piston 45 or plunger is driven from the main crank shaft by belting, as indicated at y; and x is the pipe line, which I have termed the pump line, leading from the pump to the casing C of the suction check valve.

In the normal operation of the apparatus, 50 the liquid forced through the pump line x by the pump D, exerts upon the suction check-valve in the casing C a pressure sufficient to hold it open against the opposing pressure in the suction line B.

55 Whenever for any reason the pump stops, the pressure in the pump line is automatically at once reduced, permitting the suction check valve to be shut by the pressure in the suction line, thus closing the suction line 60 tight from any escape of ammonia.

Having thus indicated in a general way the arrangement of the devices in which my invention is comprised, and their relations to one another and to the compressor and 65 its connections, I proceed to a more particu-

lar description of the construction, arrangement and operation of said devices by reference to the other figures of the drawings.

The suction-check-valve and its immediate surrounding connections are shown in the 70 sectional Fig. 2—the arrows in this figure representing the direction of the flow of the ammonia through the valve casing C, which casing, as indicated in Fig. 1, is interposed in the suction line between the main B and its branches B' which lead to the suction ends of the two compressor cylinders A.

E is a puppet valve, the suction-check-valve hereinbefore referred to, and c is the seat in the casing for said valve. The closing or seating movement of the valve is downward and in the direction of the flow of the ammonia; the opening movement of the valve is upward and in a direction against the flow of the ammonia. The check valve-proper is provided below with the usual 80 guide wings e, and above with a piston-like head e' supported on webs e², which head fits and is adapted to move up and down in a cylindrical chamber c' in the top of the 90 casing closed by a removable top or cap c² tightly bolted to the body of the casing. In the wall of this cylindrical chamber is a passage c³ leading from the interior of the casing C above valve E to the upper part 95 of chamber c' to permit pressure in the suction line to be exerted upon the head e' from above as well as from below.

In the bottom of the valve casing, directly 100 below the check valve, is an opening in which closely fits the neck of a bonnet F which is bolted to, and makes a fluid tight connection with, the valve casing. The bonnet for a portion of its length is cored out from its upper end to provide a cylindrical 105 chamber f' to receive a piston or plunger f² which fits and can move up and down in said chamber, and has on its upper end a vertically projecting stem f³ which moves up 110 and down with the piston f² and is designed to bear centrally against the under face of, and lift, the check valve when the piston is elevated, and, on the other hand, to permit the check valve to drop and seat itself when the piston is in its low position.

Below the cylindrical chamber f' there is another chamber f⁴ in the bonnet F, into which the pump line pipe x enters, and which forms virtually the terminal of the pump line. The two chambers f' and f⁴ are 120 separated by a partition f⁵ which forms the top of the lower chamber and the bottom of the upper chamber; and which has in it a central opening f⁶ through which the fluid under pressure—preferably oil—will pass 125 from the chamber f⁴ into the chamber f', to there exert its upward pressure upon the piston f².

The lower end of the bonnet F is closed by a smaller bonnet G which screws into the 130

- internally screw-threaded lower end of bonnet F and makes a fluid tight joint therewith, and forms the bottom of the chamber f^4 . The outer end of the bonnet G is closed by a packing nut g and a gland g' which screws tight onto the body of the bonnet G and up against the head of the packing nut as shown. The interior of the bonnet G is screw threaded for a portion of its length to receive the correspondingly externally screw threaded portion of a spindle H, which passes through the bonnet as shown and has above its screw threaded portion a cylindrical end of smaller diameter 15 which passes through the chamber f^4 in bonnet F loosely up through the hole f^6 in the partition f^5 so as not to prevent the flow of oil or other fluid therethrough, and up into the cylindrical chamber f^1 in a position 20 where it may bear against and lift the piston f^2 whenever occasion arises for such action. The spindle for this purpose is manipulated by a suitable handle or hand wheel h. In the position shown in Fig. 2, the spindle H 25 has been screwed up enough to slightly lift the piston f^2 from its lowest position to a position in which its vertical stem f^3 just reaches the check valve, without, however, lifting it.
- 30 The purpose of the screw spindle H is to provide a ready means for elevating the plunger or piston f^2 and thus lifting and holding the check valve off its seat, in case the fluid pressure is not available for the 35 purpose, which would happen if the oil pump during the operation of the apparatus were stopped for any purpose, as for packing, repairs, etc. The spindle H, it will be noted, has on it a bevel annular valve seat 40 h' , to engage a corresponding cylinder seat f^7 on the under face of the partition f^5 surrounding the hole f^6 therein, so that when the spindle is screwed up to lift the check valve to proper height, the two seats h' and f^7 will meet one another and thus shut off the piston chamber f^1 entirely from the pump line, thus preventing any leakage of 45 ammonia from the suction line into the pump line which in these circumstances might 50 otherwise occur owing to absence of pressure in the pump line.
- I proceed now to a description of the pump and its immediate accessories, reference for this purpose being had more particularly to Figs. 3-6 inclusive, which, as before said, represent the preferred embodiment of these devices.
- D is an upright cylindrical casting containing the pump cylinder J and the pot or 55 reservoir J' for the fluid—preferably oil. Above the pump cylinder and oil reservoir, and within the casting, are two chambers L, M, their outer walls formed by the walls of the casting D and their inner walls by a 60 dividing partition N between them—shown clearly in dotted lines in the plan view Fig. 5. The chamber L is a closed air tight chamber, communicating with, and receiving the oil from, the pump cylinder J, and connected to the pump line α , which enters its top as shown more particularly in Fig. 4, and leads from thence to the suction check valve case C as already described.
- The pump cylinder above and below is provided with ordinary or suitable valves, 70 such as the valve disks j and central guide spindles on which they are mounted, which serve in the usual way to guide and limit their movement. At a suitable point in the wall of the cylinder is formed an opening 75 through which the closely fitting horizontal reciprocating pump plunger or piston K extends from the oil reservoir. The piston at its end outside the pump cylinder is joined by a yoke K' to a piston guide K^2 , 80 both piston and piston guide moving as one, and being supported in suitable bearings in which they can reciprocate. The reciprocating movement of the pump piston—which is of limited extent—is effected by means of 85 an eccentric σ which is located in an opening left for that purpose between the interior opposite ends of the piston K and its guide K^2 , as shown in Fig. 4, and is secured on and revolves with a horizontal drive shaft O 90 located in the oil reservoir at right angles to, and on the same level with, the piston and its guide, and mounted in bearings in the casting D in which it can rotate. The drive shaft O can be actuated by any suitable means. One means for that purpose is 95 shown more particularly in Figs. 4 and 6 of the drawings, and will be presently described.
- When the pump is in operation, the reciprocation of the pump plunger K sucks oil 100 from the bottom of the oil pot or reservoir J' up through the lower valve j into the pump cylinder and discharges it through the upper valve j from the oil cylinder into 105 the closed chamber L above, as will be understood without further explanation. Continued action of the pump results in the accumulation of oil above until it fills the chamber L and the oil line α up to the suction-check-valve operating-piston, and then 110 accumulates pressure in the pump line until it is so far superior to the opposed pressure in the suction line as to lift and hold open the suction-check-valve. If the pump line 115 were hermetically closed against escape of oil, the pressure in the line would in time increase much beyond the point needed to hold the check valve open. To relieve this excessive pressure, I form in the wall or 120 partition between the two chambers L, M, a communicating opening normally closed by a spring-controlled relief valve of any suitable or known construction, such as shown in longitudinal axial section at P Fig. 130

4, with an adjusting screw P' to regulate the compression of the closing spring in order to permit said valve to open when the pressure in chamber L exceeds a predetermined limit, the excess of oil discharging through the opening in the partition from the closed chamber L into the open chamber M , whence it can be returned to the oil pot J' through any suitable channel, provided in the present instance by the gage glass J^2 on the exterior of the casting D , the lower end of said glass opening into the oil pot and its upper open end into the floor of the chamber M . Oil thus discharged through the relief valve into this open chamber, flows over its floor to the open end of the gage glass, down through which it returns to the oil pot.

It is requisite to locate at some convenient point in the pump line, between the pump and the suction-check-valve, a valve controlling an opening through which the fluid contents of the pump line may discharge, in order to relieve the suction-check-valve of pump line pressure and allow it to close. This control valve is shown at R in Fig. 3, as located in the top of the closed chamber L . In an opening in the top of this chamber is tightly secured a vertical bonnet R' , having on its lower end (which opens into chamber L) a valve seat r' . To this outlet is applied the valve R , from below the bonnet, provided with a stem r^2 which passes up through and projects above the top of the bonnet, and is pressed down a direction to open the valve by suitable means, typified by the counterweighted lever R^3 hinged to yoke R^4 encircling the upper end of the bonnet and held in place thereon by a lock nut R^5 . On the control valve is a seat r coacting with the bonnet seat r' to close the outlet when the valve is lifted. This lifting motion of the valve is occasioned by the pressure in the pump line, which, when the machine is in action, normally exceeds the opposed pressure of the counter-weight, and thus closes the control valve R . The stem of the valve has an enlarged head r^2 which fits snugly the upper interior cylindrical portion of the bonnet, and on the lower portion of the stem, which is of less diameter than the head, are the usual radial guide wings r^3 . At a point in the side of the bonnet R' below the enlarged head portion r^2 of the valve stem, is an opening r^4 through which the fluid contents of the pump line which pass up into the bonnet, when the control valve is opened, may freely discharge, thus relieving instantly the pump line pressure upon the suction check valve. I prefer to fit this opening with a suitable controlling device such as the bib cock r^5 , the nozzle of which overhangs an opening in the top of the chamber M screened by a wire strainer r^6 for catching whatever solid matter may be in the liquid

which discharges from the cock. This liquid passes through the strainer into the open chamber M , and thence back to the oil pot through the gage glass.

The bib cock r^5 is normally open while the machine is in operation. It must be closed when starting the pump, until pressure sufficient to lift and close the control valve R has been established in the pump line x ; after which it is opened.

Under the conditions thus far described, it will be noted that if, during the normal operation of the machine with pressure in the pump line sufficient to hold the suction check valve open, there should be breakage on the suction side of the compressor, or between it and the suction-check-valve, and the engine, and consequently the machine and the pump, should be shut down, yet even after such stoppage of the pump, the suction-check-valve would still be held open by the accumulated confined pressure in the pump line, thus permitting the continued discharge of the contents of the suction line through the break. It becomes necessary, therefore, to provide a means to bring about, under these conditions, a reduction of pressure in the pump line sufficient to permit the counterweighted control valve R to drop and thus throw open the discharge outlet of the pump line. This result I attain by providing in the pump line a "bleeder" so-called—that is to say, an orifice which allows the continuous leakage or restricted escape of a fluid after the valve proper (in this instance the valve R) which controls the escape of said fluid is closed. This bleeder may be located at any suitable point in the pump line between the pump and the suction-check-valve. I prefer to locate it in the control valve R and its immediate surroundings, as shown in Fig. 3.

In this figure the bleeder passage s is shown, partly in dotted lines and partly in section, as extending up centrally through the control valve R and its stem to a point just below the enlarged head r^2 of the stem, and adjoining the outlet r^4 in the side of the bonnet R' controlled by the bib cock r^5 . At this point, branch orifices s', s'' , are made leading laterally from the main bleeder passage s through the sides of the valve stem. Under this arrangement, it will be noted that the restricted flow of the fluid from the bleeder will be carried off and returned to the oil pot by the same route as that followed by the main discharge consequent upon the opening of the control valve proper R . Another advantage of this arrangement is that, if the pump, during the operation of the machine, be temporarily stopped for any reason, it is still possible, by closing the cock r^5 and thus preventing escape of the fluid from the bleeder, to maintain, for quite some time, in the pump line pressure sufficient to hold the suction check

valve open, thus permitting the continued flow of the ammonia gas from the suction line to the compressor.

- In the case of the shutting down of the 6 pump, with the bib cock r^5 open (which is its normal condition), the leakage through the bleeder will almost immediately reduce the pressure in the pump line sufficiently to allow the counter weight on the control valve 70 R to preponderate, thus opening said valve and at once relieving the pressure in the pump line and permitting the suction-check-valve to close. The counter weight on the valve may be so proportioned as to permit it 75 to preponderate upon any predetermined reduction of pressure in the pump line. The bleeder leakage may be varied if desired by any suitable means. I employ for this purpose, in the present instance, a screw threaded 80 bleeder-regulating pin s^2 (Fig. 3) located in the internally screw threaded axial hole in the head r^2 of the valve stem R, with its taper point protruding into the upper end of the main bleeder passage s as shown. By 85 screwing the regulating pin up or down, the dimensions of the discharge orifice of the bleeder passage s can be varied as desired.

It remains to describe the means for driving the pump.

- 90 As indicated in the opening part of the specification and as shown in Fig. 1 of the drawings, the pump is driven from the same engine that drives the compressor, typified by the main crank shaft X, getting its motion from said shaft by belting y running from said shaft to a pulley on the pump casing D—said pulley, lettered T, being shown in Figs. 1, 4 and 6. The pump thus 95 stops and starts with the engine.

- 40 Any suitable intermediaries for communicating movement from the pulley T to the eccentric drive shaft O for the pump plunger, may be employed. As shown in Figs. 4 and 6, they consist, in the present 100 instance, of a ratchet wheel t fast on drive shaft O, having a detent t^2 to prevent its back action, and engaged by a spring 105 pressed driving pawl t^3 pivoted to the lower end of a pawl arm t^4 whose upper end 110 swivels on a crank pin t^4 projecting from the face of pulley T. Further explanation of this driving mechanism is unnecessary, 115 and its mode of operation is obvious.

- The suction-check-valve E automatically 120 closes and remains closed when the engine stops and the plant closes down. In again starting, the refrigerating machine can be started up with this valve closed, in which case the compressor will lower the pressure 125 to the extent of a vacuum or partial vacuum in the suction pipe connections between this valve and the compressor, until the pump, which also started up along with the refrigerating machine, has developed in the 130 pump line sufficient pressure to close the

control valve R and raise the suction check valve E off its seat, after which normal operation is established.

In belt driven compressors, it is customary to have a by-pass connection between the discharge header and suction header of the refrigerating system, so that the compressor may start up without the full load on the motor. In such case the by-pass valve is opened, thus cutting out the condenser 75 and refrigerating coil, and establishing a short circuit between the headers, and consequently practically equalizing the pressures on the suction and discharge sides of the compressor. When the machine has attained its normal speed (at which time the by-pass valve is closed), the pressure in the pump line will have increased sufficiently to open the suction-check-valve.

Probably, however, the preferable way, in starting up the machine, whether belt-driven or not, would be to lift the suction-check-valve E slightly off its seat by means of the manually operated spindle H. Then, after the machine attains its normal speed, and the suction-check-valve has been elevated to the full extent by the pressure established in the pump line, the spindle should be lowered far enough to allow the valve to seat itself whenever the machine stops. It 90 is with this, among other things, in view that the manually operated spindle H has been provided.

It may be desirable at times, in case of emergency for example, to be able to control the pump line from a remote point, and independently of the driving shaft of the compressor, in such manner as to at once relieve the pressure in the pump line and permit the suction-check-valve to close. To this end I may interpose in the pump line a valve, which I term "remote-control valve," normally closing and holding closed a discharge outlet in the pump line against the pressure in said line, and adapted to be 100 lifted to open the discharge outlet by manually operated means leading from the valve to the engine room or other preferred locality remote from the compressor. Various arrangements of devices may be used 105 for this purpose. That shown in Fig. 7 comprises a pop-valve v controlling an outlet v' in the pump line x to the atmosphere, and counter-weighted, or equivalently counter-pressed as indicated at v^2 to be held tight 110 closed against pressure in the pump line x , in combination with suitable intermediaries between said valve v and the remote-control, or valve-operating point, typified by the wire cord v^3 attached to the counter-weight 115 v^2 and leading, from thence over suitable guide sheaves v^4 to the engine room or other remote control point, where it will be provided with a handle by which the cord v^3 can be pulled in a direction to raise the 120

counter-weight and permit the pressure in the pump line to lift the thus-liberated valve and discharge through the outlet v' to the atmosphere, thus as once relieving the pressure in the pump line and allowing the suction-check-valve to close, this condition of things continuing so long as the valve v is free from the controlling pressure of its counter-weight v^2 —even with the compressor and pump in continued action. On release of the counter-weight v^2 it drops, thus closing the valve v , whereupon, under the action of the pump, pressure again accumulates in the pump line, until it is sufficient to again open and hold open the suction-check-valve. The oil discharging from the pump line through outlet v' may be returned to the oil pot of the pump by any suitable means. The part v^5 in this figure 20 is merely a support located at the elbow x' in the pump line x to sustain the line at that point.

Having described my improvement and the best way now known to me of carrying it into effect, I state in conclusion that I do not limit myself narrowly to the structural details hereinbefore described and shown in the accompanying drawings in illustration of my invention, since manifestly the same can be varied considerably without departure from the spirit of the invention; but what I claim herein as new and desire to secure by Letters Patent, is as follows:

35 1. In refrigerating or ice making apparatus, the combination with the compressor, the refrigerating coil, and the suction line including the refrigerating coil and leading to the suction side of the compressor, of a 40 check valve interposed in the suction line between the refrigerating coil and the compressor, whose closing movement is in the direction of the flow of the fluid in the suction line, and means extraneous to, and independent of, the fluid circulating system 45 in which the suction line is included, adapted and arranged to exert upon the check valve during the normal operation of the compressor a superior pressure in a direction to open it and hold it open against the pressure in the suction line, said check valve being automatically closed by the pressure in the suction line whenever the superior pressure exerted by said extraneous means 50 is removed.

2. The combination with the compressor, the refrigerating coil, and the suction line including the refrigerating coil and leading to the suction side of the compressor, of a 60 check valve interposed in the suction line between the refrigerating coil and the compressor, whose closing movement is in the direction of the flow of the liquid in the suction line; a pump, pump-driving means, and a reservoir from which the pump draws

its supply of liquid; a pump line to the check valve through which liquid under pressure is forced by the pump in a direction to open the check valve against the opposing pressure in the suction line; a discharge opening in the pump line at a point between the pump and the check valve for the escape of liquid from the pump line; and a control valve for said opening arranged and adapted to close and be held closed by the pressure in the pump line established by the action of the pump, and adapted to open whenever that pressure falls below a predetermined limit, to permit the free escape of the liquid from the pump line, and the consequent closing of the suction-check-valve.

3. The combination with the compressor, the refrigerating coil, and the suction line including the refrigerating coil and leading to the suction side of the compressor, of a check valve interposed in the suction line between the refrigerating coil and the compressor and adapted to be closed by pressure of the fluid in the suction line; a pump, pump-driving means, and reservoir from which the pump draws its supply of liquid; a pump line leading from the pump to the check valve, through which liquid under pressure is forced from the pump in a direction to open the check valve against the opposing pressure in the suction line; a discharge opening in the pump line at a point between the pump and the check valve; a control valve for said opening, closed by pressure in the pump line, and opened whenever said pressure falls below a predetermined limit; and a bleeder also located in the pump line between the pump and the check valve, through which continuous leakage or restricted escape of liquid from the pump line takes place after the closing of the control valve.

4. The combination with the compressor, refrigerating coil, suction line, and check valve interposed in the suction line between the refrigerating coil and the compressor, of the force pump, the pump line between said pump and the check valve, through which liquid under pressure is forced by the pump to open the check valve against the pressure in the suction line, and manually operable means adapted to lift and open the check valve independently of the pressure in the pump line.

5. The combination with the compressor, refrigerating coil, suction line, and check valve interposed in the suction line between the refrigerating coil and the compressor, of the pump; the pump line between the pump and the check valve, through which liquid under pressure is forced by the pump to open the check valve against the pressure in the suction line; a discharge opening in the pump line at a suitable point between the pump and the check valve.

the pump and the check valve; a control valve for said opening, closed by pressure in the pump line, and opened whenever said pressure falls below a predetermined limit; 5 a housing for said control valve; a valve or cock-controlled outlet in said housing for escape of liquid passing from the pump line through said discharge opening; and a bleeder extending from the interior of the 10 pump line through the control valve, and arranged and adapted to discharge through the outlet in the control valve housing.

6. The combination with the compressor, refrigerating coil, suction line, and check 15 valve interposed in the suction line between the refrigerating coil and the compressor,

of the force pump, the pump line through which liquid under pressure is forced by the pump to open the suction-check-valve against the pressure in the suction line, a 20 discharge outlet in the pump line, a counter-pressed remote-control valve which normally closes and holds closed said outlet against pressure in the pump line, and manually operable means whereby said remote-control valve may be opened at will to permit the relief, through the outlet controlled by it, of the pressure in the pump line, substantially as and for the purposes hereinbefore set forth.

In testimony whereof I affix my signature.
THOMAS SHIPLEY.
